(57) **CLAIM**

The ornamental design for a head mounted display device, as shown and described.

DESCRIPTION

FIG. 1 is a perspective view of a head mounted display device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, the article in a position of use;

FIG. 9 is a front view thereof, but with a portion of the article shown as transparent; and,

FIG. 10 is a left side view thereof, showing the display portion of the article in broken lines and in an alternate position of use.

The broken lines are just for illustrative purposes only and form no part of the claimed design.
